(57) **ABSTRACT**

A developing device includes a developing container, a first agitating feeding member, a second agitating feeding member, a first developer delivery portion, a second developer delivery portion, and a toner sensor. The developing container includes a first transport path and a second transport path. The first agitating feeding member and the second agitating feeding member agitate and feed developer. The first developer delivery portion delivers the developer from the first transport path to the second transport path. The second developer delivery portion delivers the developer from the second transport path to the first transport path. The toner sensor is disposed at a part of the first transport path near the first developer delivery portion. A ceiling height of a part of the first transport path facing the first developer delivery portion is larger than a ceiling height of other part of the first transport path.

DEVELOPING DEVICE AND AN IMAGE FORMING APPARATUS INCLUDING THE SAME

CROSS-REFERENCE TO RELATED APPLICATIONS

This application is based upon and claims the benefit of priority from the corresponding Japanese Patent Application No. 2013-192557, filed Sep. 18, 2013, the entire contents of which are incorporated herein by reference.

BACKGROUND OF THE INVENTION

The present disclosure relates to a developing device mounted in an image forming apparatus such as a copier, a facsimile, a printer, or the like, and the image forming apparatus including the same. In particular, the present disclosure relates to a developing device adapted to suppress aggregation and adhesion of developer and an image forming apparatus including the developing device.

Conventionally, as a developing method using dry toner in an image forming apparatus using an electrophotographic process, there are known a one-component developing method using one-component developer consisting of magnetic toner or non-magnetic toner and a two-component developing method using two-component developer for charging non-magnetic toner by magnetic carrier, in which a magnetic brush constituted of magnetic carrier and toner formed on a developing roller develops an electrostatic latent image on an image carrier (photoreceptor).

In the developing device described above, the toner is consumed by a developing operation. Therefore, a toner sensor for detecting toner density (or toner amount) is disposed in the developing device, and new toner is supplied in accordance with amount of toner consumed by developing. In this case, when charging amount of newly supplied toner is not sufficient, an image defect such as toner scattering or fog may occur. Therefore, in the two-component developing method, it is necessary to sufficiently agitate and mix the toner and the carrier so that the toner is charged to a predetermined charge amount. In addition, also in the one-component developing method, it is necessary to sufficiently mix the toner in the developing device with newly supplied toner so that charge amount distribution becomes uniform.

Therefore, there is a widely used method in which a circulation path of developer is disposed in the developing device, and an agitating feeding member having a screw shape constituted of a rotation shaft and a helical blade disposed in the circulation path agitates and mixes the developer so as to circulate and feed the same. Specifically, in a developing device 101 as illustrated in FIG. 18, an inside of a developing container 102 is divided into a first transport path 105 and a second transport path 107 by a partition wall 103. A first spiral 109 and a second spiral 110 for mixing, agitating, and feeding the developer are disposed in a rotatable manner in the first transport path 105 and in the second transport path 107.

Then, the developer is agitated and transported in an axis direction (directions of arrow A1 and arrow A2 in FIG. 18) by the first spiral 109 and the second spiral 110, and is circulated between the first transport path 105 and the second transport path 107 via developer delivery portions 111a and 111b formed on both ends of the partition wall 103. In other words, the first transport path 105, the second transport path 107, and the developer delivery portions 111a and 111b form the circulation path of the developer in the developing container 102.

Here, as higher image forming speed is required in recent years, it has become necessary to increase also a circulation speed (feed speed) of the developer in the developing device. As a method of increasing the feed speed of the developer, there is usually a method of increasing rotation speed of the first spiral 109 and the second spiral 110 illustrated in FIG. 18 and a method of increasing a pitch of the helical blade, for example.

SUMMARY OF THE INVENTION

A developing device according to an aspect of the present disclosure includes a developing container, a developer carrier, a first agitating feeding member, a second agitating feeding member, a first developer delivery portion, a second developer delivery portion, and a toner sensor. The developing container includes a first transport path and a second transport path disposed substantially in parallel to each other, and stores developer containing toner. The developer carrier is supported in a rotatable manner in the developing container and carries developer in the second transport path on its surface. The first agitating feeding member agitates and feeds the developer in the first transport path. The second agitating feeding member agitates and feeds the developer in the second transport path in the opposite direction to the first agitating feeding member. The first developer delivery portion passes the developer from the first transport path to the second transport path. The second developer delivery portion passes the developer from the second transport path to the first transport path. The toner sensor is disposed in a part near the first developer delivery portion in the first transport path so as to detect toner amount or toner density in the developing container. A ceiling height of a part of the first transport path opposed to the first developer delivery portion is larger than a ceiling height of other part of the first transport path.

Other objects of the present invention and specific advantages obtained from the present disclosure will become more apparent from the description of embodiments given below.

BRIEF DESCRIPTION OF THE DRAWINGS

These and/or other aspects and advantages of the invention will become apparent and more readily appreciated from the following description of the embodiments, taken in conjunction with the accompanying drawings of which:

FIG. 1 is a schematic cross-sectional view illustrating an overall structure of an image forming apparatus including a developing device according to a first embodiment of the present disclosure.

FIG. 2 is a side cross-sectional view illustrating a structure of the developing device according to the first embodiment of the present disclosure.

FIG. 3 is an external perspective view of the developing device in a state where a cover member is removed according to the first embodiment of the present disclosure.

FIG. 4 is a plan cross-sectional view illustrating a structure of an agitating portion of the developing device according to the first embodiment of the present disclosure.

FIG. 5 is a perspective view illustrating a structure of a first spiral of the developing device according to the first embodiment of the present disclosure.

FIG. 6 is a cross-sectional view illustrating a structure around a first developer delivery portion of the developing device according to the first embodiment of the present disclosure.

FIG. 7 is a perspective view illustrating a structure of a developer feeding member of the developing device according to the first embodiment of the present disclosure.

FIG. 8 is a plan cross-sectional view illustrating a structure of the agitating portion of the developing device according to a second embodiment of the present disclosure.

FIG. 9 is a perspective view of a structure of the first spiral of the developing device of the second embodiment of the present disclosure.

FIG. 10 is an enlarged perspective view illustrating a structure around a paddle portion of the first spiral of the developing device according to the second embodiment of the present disclosure.

FIG. 11 is a plan cross-sectional view illustrating a structure of the agitating portion of the developing device according to a third embodiment of the present disclosure.

FIG. 12 is an enlarged perspective view illustrating a structure around the paddle portion of the first spiral of the developing device according to the third embodiment of the present disclosure.

FIG. 13 is a plan cross-sectional view illustrating a structure around the first developer delivery portion of the developing device according to the third embodiment of the present disclosure.

FIG. 14 is a cross-sectional view illustrating a structure around the first developer delivery portion of the developing device according to Comparative Example 1.

FIG. 15 is a graph showing a result of measuring a sensor output value (V) and toner weight (g) every 500 sheet printing when continuous printing is performed using the developing device of Example 1.

FIG. 16 is a graph showing a result of measuring the sensor output value (V) and the toner weight (g) every 500 sheet printing when continuous printing is performed using the developing device of Example 2.

FIG. 17 is a graph showing a result of measuring the sensor output value (V) and the toner weight (g) every 500 sheet printing when continuous printing is performed using the developing device Comparative Example 1.

FIG. 18 is a plan cross-sectional view illustrating an example of a conventional developing device.

DETAILED DESCRIPTION OF THE EMBODIMENTS

Now, embodiments of the present disclosure are described with reference to the drawings.

First Embodiment

With reference to FIG. 1 to FIG. 7, a structure of an image forming apparatus 100 including a developing device 4 according to a first embodiment of the present disclosure is described. In the image forming apparatus (for example, a monochrome printer) 100, when performing an image forming operation, an image forming unit P in the apparatus main body forms an electrostatic latent image based on document image data transmitted from a personal computer (PC) (not shown), and the developing device 4 forms a toner image by adhesion of toner to the electrostatic latent image. The toner is supplied to the developing device 4 from a toner container 5. Further, in this image forming apparatus 100, a photoreceptor drum 1 is rotated in a clockwise direction in FIG. 1 while the image forming process is performed onto the photoreceptor drum 1.

The image forming unit P includes a charging unit 2, an exposing unit 3, the developing device 4, a transfer roller 6, a

cleaning device 7, and a charge neutralizer (not shown), which are disposed along a rotation direction of the photoreceptor drum 1 (clockwise direction). The photoreceptor drum 1 includes, for example, an aluminum drum and a photosensitive layer laminated on the aluminum drum, and a surface thereof is charged by the charging unit 2. Then, the surface receives a laser beam from the exposing unit 3 described later so that an electrostatic latent image is formed with decreased charges. Note that the above-mentioned photosensitive layer is not particularly limited but is preferably, for example, an amorphous silicon (a-Si) layer superior in durability or an organic photosensitive layer (OPC) that generates little ozone in charging and can provide a high resolution image.

The charging unit 2 uniformly charges the surface of the photoreceptor drum 1. For instance, as the charging unit 2, a corona discharge device is used, which generates discharge by applying a high voltage to a thin wire or the like as an electrode. Note that instead of the corona discharge device, it is possible to use a contact type charging device that applies a voltage to a charging member such as a charging roller contacting with the photoreceptor surface. The exposing unit 3 irradiates the photoreceptor drum 1 with a light beam (for example, the laser beam) based on image data so as to form the electrostatic latent image on the surface of the photoreceptor drum 1.

The developing device 4 forms a toner image with toner adhered to the electrostatic latent image on the photoreceptor drum 1. Note that one-component magnetic developer (hereinafter also referred to simply as toner) including only magnetic toner component is stored in the developing device 4 in this example. In addition, a detailed structure of the developing device 4 will be described later. The transfer roller 6 correctly transfers the toner image formed on the surface of the photoreceptor drum 1 onto the paper sheet transported in a paper sheet transport path 11. The cleaning device 7 includes a cleaning roller or a cleaning blade that linearly contacts with the photoreceptor drum 1 in a longitudinal direction so as to remove residual toner remaining on the surface of the photoreceptor drum 1 after the toner image is transferred onto the paper sheet.

Further, the exposing unit 3 irradiates the photoreceptor drum 1 with the laser beam (light beam) based on the image data input in advance so that the electrostatic latent image based on the image data is formed on the surface of the photoreceptor drum 1. After that, the developing device 4 causes the toner to be adhered to the electrostatic latent image so that the toner image is formed.

As described above, the paper sheet is transported from a paper sheet storing unit 10 to the image forming unit P with the formed toner image via the paper sheet transport path 11 and a registration roller pair 13 at a predetermined timing. Then, in the image forming unit P, the toner image on the surface of the photoreceptor drum 1 is transferred onto the paper sheet by the transfer roller 6. Further, the paper sheet with the transferred toner image is separated from the photoreceptor drum 1 and is transported to a fixing unit 8 in which the paper sheet is heated and pressed so that the toner image is fixed to the paper sheet. The paper sheet after passing the fixing unit 8 passes a discharge roller pair 14 and is discharged onto a paper sheet discharge portion 15.

As illustrated in FIG. 2, the developing device 4 includes a developing roller (developer carrier) 20, a restricting blade 21, an agitating feeding member 30, a developer feeding member 35, and a developing container 40 housing these members. Note that FIG. 2 illustrates a state viewed from a

rear side in FIG. 1, and a layout of the members in the developing device 4 is opposite to FIG. 1 in the left and right direction.

The developing container 40 forms an outer sheath of the developing device 4 and includes a main body 41 having an open upper surface and a cover member 42 that covers the upper surface of the main body 41. The developing container 40 is divided into a first transport path 40a and a second transport path 40b by a partition wall 41a formed in the main body 41. The first transport path 40a and the second transport path 40b store the one-component developer containing only the magnetic toner. In addition, the developing container 40 supports the agitating feeding member 30, the developer feeding member 35, and the developing roller 20 in a rotatable manner. Further, the developing container 40 is provided with an opening 40c that exposes the developing roller 20 to the photoreceptor drum 1 (see FIG. 1).

The developing roller 20 is disposed to be opposed to the photoreceptor drum 1 with a certain space. In addition, the developing roller 20 supplies the toner to the photoreceptor drum 1 in an opposing region close to the photoreceptor drum 1. The agitating feeding member 30 is disposed in a lower left of the developing roller 20. In addition, the restricting blade 21 is fixed and held by the developing container 40 at left of the developing roller 20.

The agitating feeding member 30 is constituted of a first spiral (first agitating feeding member) 31 and a second spiral (second agitating feeding member) 32. The second spiral 32 is disposed in the second transport path 40b at lower left of the developing roller 20, and the first spiral 31 is disposed in the first transport path 40a at left next to the second spiral 32.

The first and second spirals 31 and 32 agitate and feed the developer. In addition, developer delivery portions (a first developer delivery portion 40d and a second developer delivery portion 40e described later) are disposed on both ends in the longitudinal direction (perpendicular to the plane of FIG. 2) of the partition wall 41a separating between the first transport path 40a and the second transport path 40b. When the first spiral 31 rotates, the developer is transported from one of the developer delivery portions (first developer delivery portion 40d) formed in the partition wall 41a to the second spiral 32, and hence the developer circulates in the first transport path 40a and the second transport path 40b. Further, the developer is supplied from the second spiral 32 to the developing roller 20.

The developing roller 20 includes a fixed shaft 20a, a magnetic pole member 20b, and a developing sleeve 20c formed of a non-magnetic metal material in a cylindrical shape. The developing roller 20 is rotated in a clockwise direction in FIG. 2 by a drive mechanism (not shown) including a motor and gears.

When the developing sleeve 20c to which a developing bias is applied rotates, the developer (toner) carried on the surface of the developing sleeve 20c flies to the photoreceptor drum 1 due to a potential difference between a developing bias potential and a potential of the exposed part on the photoreceptor drum 1 in a developing region (opposite region between the developing roller 20 and the photoreceptor drum 1). The flying toner is sequentially adhered to the exposed part on the rotating photoreceptor drum 1, and hence the electrostatic latent image on the photoreceptor drum 1 is developed.

As illustrated in FIG. 3 and FIG. 4, the partition wall 41a, the first transport path 40a, the second transport path 40b, and the developer delivery portions 40d and 40e are formed in the developing container 40. In addition to them, a developer supply passage 40f is formed. This developer supply passage

40f is a passage for supplying new developer (supplied toner) from the toner container 5 to the first transport path 40a.

The first transport path 40a, the second transport path 40b, and the developer supply passage 40f are disposed in parallel to each other. The partition wall 41a extending in the longitudinal direction of the developing container 40 is disposed to separate between the first transport path 40a and the second transport path 40b. A partition wall 41b extending in the longitudinal direction of the developing container 40 is disposed to separate between the developer supply passage 40f and the first transport path 40a. Note that in the first transport path 40a, the left side of FIG. 3 is referred to as an upstream side, while the right side of FIG. 3 is referred to as a downstream side. In addition, in the second transport path 40b, the right side of FIG. 3 is referred to as an upstream side, while the left side of FIG. 3 is referred to as a downstream side.

The first developer delivery portion 40d and the second developer delivery portion 40e are formed on one side and on the other side in the longitudinal direction of the partition wall 41a (A1 direction side and A2 direction side). The first developer delivery portion 40d connects A1 direction ends of the first transport path 40a and the second transport path 40b. The second developer delivery portion 40e connects A2 direction ends of the first transport path 40a and the second transport path 40b. Then, the developer can circulate in the first transport path 40a, the first developer delivery portion 40d, the second transport path 40b, and the second developer delivery portion 40e.

A toner sensor 43 for detecting developer amount (toner amount) in the developing container 40 is disposed on an inner wall near the first developer delivery portion 40d of the first transport path 40a. As the toner sensor 43, a permeability sensor for detecting permeability of the toner (magnetic one-component developer) in the developing container 40 is used. The toner sensor 43 detects permeability of the toner and outputs a voltage value corresponding to the detection result to a control unit (not shown). The control unit determines toner remaining quantity from the output value of the sensor. Then, in accordance with the detection result of the toner sensor 43, the developer (toner) stored in the toner container 5 (see FIG. 1) is supplied to the developing container 40 via a supply port 42a. Note that as the toner sensor 43, it is also possible to use a piezoelectric sensor obtaining an electric signal when a pressure is applied to its detection surface besides the above-mentioned permeability sensor.

A rotation shaft 31a of the first spiral 31 is provided with a cleaning member 45 made of a spring material. When the first spiral 31 rotates, the cleaning member 45 also rotates so as to clean the detection surface of the toner sensor 43.

As illustrated in FIG. 3 to FIG. 5, the first spiral 31 includes the rotation shaft 31a pivoted to the developing container 40 in a rotatable manner, and a first helical blade (transporting blade) 31b having a substantially arc shape formed integrally with the rotation shaft 31a in a helical shape at a constant pitch in an axis direction of the rotation shaft 31a. The first helical blade 31b is designed to have thickness (length in the longitudinal direction) increasing from an outer edge part to the rotation shaft 31a, so as to agitate and feed the developer in the first transport path 40a in the A1 direction. The rotation shaft 31a and the first helical blade 31b are molded integrally using resin such as ABS resin to which the developer is hardly adhered.

As illustrated in FIG. 4, the second spiral 32 has the same structure as the first spiral 31 except for a different direction (phase) of the helical blade. In other words, the second spiral 32 includes a rotation shaft 32a and a second helical blade 32b that is formed integrally with the rotation shaft 32a in a helical

shape at the same pitch as the first helical blade **31b** in the axis direction of the rotation shaft **32a** but in the opposite direction (opposite phase) to the first helical blade **31b**. The rotation shaft **32a** is disposed in parallel to the rotation shaft **31a** and is pivoted to the developing container **40** in a rotatable manner. The second helical blade **32b** agitates the developer in the second transport path **40b** in the A2 direction (opposite to the A1 direction) and supplies the developer to the developing roller **20**.

As illustrated in FIG. 6, a distance between the main body **41** and the cover member **42** (hereinafter referred to as a ceiling height) at a part of the first transport path **40a** facing the first developer delivery portion **40d** is larger than a ceiling height of other part of the first transport path **40a** (part other than the part facing the first developer delivery portion **40d**). Note that as the ceiling height is larger, the developer hardly reaches the ceiling so that aggregation of the developer can be suppressed, though the developing container **40** becomes larger. Therefore, it is preferred to set the ceiling height at the part of the first transport path **40a** facing the first developer delivery portion **40d** to be larger than the ceiling height of other part of the first transport path **40a** by approximately 8 mm to 15 mm.

As illustrated in FIG. 4, in a part of the developer supply passage **40f** on the A1 direction side, the supply port **42a** for supplying new developer (toner) to the developing container **40** from the toner container **5** disposed above the developing container **40** is formed in the cover member **42**.

The developer supply passage **40f** is a passage for transporting the developer supplied to a part on the A1 direction side to the A2 direction so as to supply the developer to the upstream side of the first transport path **40a**. A supplying portion **40g** for supplying the developer from the developer supply passage **40f** to the first transport path **40a** is formed in the developer supply passage **40f**. The supplying portion **40g** is formed on the upstream side (right side in FIG. 4) of the downstream side end (left end in FIG. 4) of the developer supply passage **40f** in the developer transport direction (A2 direction) in the developer supply passage **40f**, and on the downstream side (left side in FIG. 4) of the supply port **42a**.

In the developer supply passage **40f**, the developer feeding member **35** is disposed in parallel to the first spiral **31** and the second spiral **32**. As illustrated in FIG. 3 and FIG. 7, the developer feeding member **35** includes a rotation shaft **35a**, and a third helical blade **35b** and a fourth helical blade **35c** that are formed integrally with the rotation shaft **35a**. The third helical blade **35b** is formed in a helical shape of a blade having the opposite direction (opposite phase) to the first helical blade **31b** in the axis direction of the rotation shaft **35a**, and is formed from the supply port **42a** (see FIG. 4) to the supplying portion **40g**. The fourth helical blade **35c** is formed in a helical shape of a blade having the opposite direction (opposite phase) to the third helical blade **35b**, and is formed from the supplying portion **40g** to the end on the A2 direction side. In addition, a transporting blade **35d** having a paddle shape is formed in a part of the rotation shaft **35a** facing the supplying portion **40g**.

The developer feeding member **35** is configured to rotate in the same direction as the first spiral **31** (counterclockwise direction in FIG. 2), and hence the developer supplied to the supply port **42a** is transported to the supplying portion **40g** side. Because the third helical blade **35b** and the fourth helical blade **35c** have phases in opposite directions, the third helical blade **35b** and the fourth helical blade **35c** cause the developer to collide at the supplying portion **40g** and to be transported to the first transport path **40a**.

Note that the developer feeding member **35**, the first spiral **31**, and the second spiral **32** are driven to rotate by a drive mechanism (not shown) including a motor and gears.

In this embodiment, as described above, the ceiling height of the part of the first transport path **40a** facing the first developer delivery portion **40d** is larger than the ceiling height of other part of the first transport path **40a**. In this way, it is possible to prevent the developer from reaching the ceiling in the part of the first transport path **40a** near the first developer delivery portion **40d**. Therefore, a bridge formation of the developer pressed by the pressure can be suppressed. Therefore, occurrence of an image defect such as fog due to collapse of a developer bridge can be suppressed. In addition, when the developer in the developing container **40** is decreased, it is possible to suppress false detection that there is sufficient developer when the toner sensor **43** detects a developer bridge.

Note that because a magnetic force or a rotation force of the developing roller **20** acts on the developer in the transport direction downstream end (left end in FIG. 4) of the second transport path **40b**, stagnation of the developer hardly occur near the second developer delivery portion **40e** for delivering the developer from the second transport path **40b** to the first transport path **40a**, and a developer bridge is hardly formed, too. Therefore, it is sufficient to increase the ceiling height only in the part of the first transport path **40a** facing the first developer delivery portion **40d**.

Second Embodiment

Next, with reference to FIG. 8 to FIG. 10, the developing device **4** of the second embodiment of the present disclosure is described.

As illustrated in FIG. 8 and FIG. 9, the developing device **4** of the second embodiment of the present disclosure includes a paddle portion **50** having a frame-like shape without the rotation shaft **31a** on the end of the first spiral **31** facing the first developer delivery portion **40d** (downstream side end in the developer transport direction).

As illustrated in FIG. 10, the paddle portion **50** has a substantially rectangular shape in a plan view surrounded by the first helical blade **31b** positioned at the most downstream side end in the developer transport direction, two first ribs **51a** and **51b** extending from the first helical blade **31b** in parallel to the rotation shaft **31a**, and a second rib **53** extending perpendicularly to the rotation shaft **31a** to connect ends of the first ribs **51a** and **51b**. The second rib **53** is connected to the rotation shaft **31a** on the surface opposite to the surface connected to the first ribs **51a** and **51b**. As illustrated in FIG. 8, the first helical blade **31b** is formed so that a part thereof overlaps the first developer delivery portion **40d** in the direction of the rotation shaft **31a** (so as to exceed the end of the partition wall **41a** and to protrude to the first developer delivery portion **40d** side).

Other structure of the second embodiment is the same as the first embodiment described above.

In this embodiment, as described above, the part of the first spiral **31** facing the first developer delivery portion **40d** is the part without the rotation shaft **31a**, while the paddle portion **50** including the plurality of first ribs **51a** and **51b** parallel to the rotation shaft **31a** is formed. In this way, because sufficient space is secured in a vicinity of the first ribs **51a** and **51b**, even if the developer is deteriorated so that fluidity is lowered, the developer can pass the space between the first ribs **51a** and **51b** so as to circulate, and adhesion of the developer to the first ribs **51a** and **51b** and to the ceiling of the developing container **40** can be suppressed more.

In addition, because the paddle portion **50** is formed using the first helical blade **31b** positioned on the most downstream side in the developer transport direction as described above, the developer can be efficiently transported to the paddle portion **50** without attenuating a driving force (transporting force) of the first helical blade **31b** in the direction of the rotation shaft **31a**.

In addition, as described above, the paddle portion **50** has a frame-like shape surrounded by the first helical blade **31b**, the two first ribs **51a** and **51b** extending from the first helical blade **31b** in parallel to the rotation shaft **31a**, and the second rib **53** extending perpendicularly to the rotation shaft **31a** to connect the ends of the first ribs **51a** and **51b**. The second rib **53** is connected to the rotation shaft **31a** on the surface opposite to the surface connected to the first ribs **51a** and **51b**. In this way, the part without the rotation shaft **31a** (paddle portion **50**) can be easily provided to the first spiral **31**, and strength of the paddle portion **50** can be easily secured.

In addition, as described above, at least a part of the first helical blade **31b** on the most downstream side in the developer transport direction is formed to overlap the first developer delivery portion **40d** in the direction of the rotation shaft **31a**. In this way, the developer can be smoothly moved from the first transport path **40a** to the second transport path **40b** in the first developer delivery portion **40d**.

Other effects of the second embodiment are the same as those of the first embodiment described above.

Third Embodiment

Next, with reference to FIG. 11 to FIG. 13, the developing device **4** of a third embodiment of the present disclosure is described.

As illustrated in FIG. 11, in the developing device **4** of the third embodiment of the present disclosure, the paddle portion **50** of the first spiral **31** is equipped with a developer breaking member **61** for breaking the developer wall formed in the first developer delivery portion **40d**.

As illustrated in FIG. 12, the developer breaking member **61** is disposed on each of outer surfaces of the first ribs **51a** and **51b**. The developer breaking members **61** are disposed at different protruding positions in the direction of the rotation shaft **31a** of the first spiral **31**. Distal ends of the developer breaking members **61** protrude in the rotation direction of the first spiral **31** (tangential direction of rotation locus of the first ribs **51a** and **51b**). When the first spiral **31** rotates, the developer breaking members **61** rotate while the distal ends thereof contact and slide on the inner wall of the first transport path **40a**. When the first rib **51a** or **51b** approaches the developer delivery portion **40d**, the distal end of the developer breaking member **61** reaches the first developer delivery portion **40d** so as to contact with a developer wall **W** formed in the first developer delivery portion **40d** (hatching part in FIG. 13).

When the first spiral **31** rotates around the rotation shaft **31a**, a driving force in the axis direction is generated in the spiral part of the first spiral **31** (region in which the first helical blade **31b** is formed), and hence the developer is transported in the A1 direction in the first transport path **40a**. In the part facing the first developer delivery portion **40d**, when the first spiral **31** rotates, the paddle portion **50** also rotates. Then, the rotation of the first ribs **51a** and **51b** causes the developer to be fed to the second transport path **40b** via the first developer delivery portion **40d**. In addition, in the first developer delivery portion **40d**, the developer is delivered to the second transport path **40b** by momentum when the developer on the upstream side is transported.

However, the first developer delivery portion **40d** has a region where the transporting force of the first spiral **31** and the second spiral **32** do not act. In particular, when the developer amount in the developing container **40** is small, pressure **5** of the developer sent out from the first transport path **40a** also becomes small. Therefore, the developer is deposited in the first developer delivery portion **40d** so that the developer wall **W** is formed to block the first developer delivery portion **40d** as illustrated in FIG. 13. As a result, the developer stagnates in **10** the vicinity of the upstream side of the first developer delivery portion **40d** so that the output value of the toner sensor **43** is increased.

On the other hand, when a predetermined amount of or **15** more developer stagnates in a vicinity of the upstream side of the first developer delivery portion **40d**, the stagnated developer presses the developer wall **W** formed in the first developer delivery portion **40d** to collapse. As a result, the developer amount in the vicinity of the upstream side of the first developer delivery portion **40d** is rapidly decreased so that the **20** output value of the toner sensor **43** is decreased. This phenomenon is repeated so that the output value of the toner sensor **43** becomes unstable.

Therefore, in this embodiment, the developer breaking members **61** provided to the first ribs **51a** and **51b** of the **25** paddle portion **50** are used for breaking the developer wall **W** in the first developer delivery portion **40d**, and hence the developer does not stagnate in the vicinity of the upstream side of the first developer delivery portion **40d**. In this way, even if the developer amount in the developing container **40** is **30** small, or the developer is deteriorated so that its fluidity is lowered, the output value of the toner sensor **43** can be stabilized. In addition, control accuracy of toner supply from the toner container **5** to the developing device **4** is also improved.

As a material of the developer breaking member **61**, it is **35** preferred to use a resin film such as a PET film that can be elastically deformed. In addition, as a width of the developer breaking member **61** (size in the direction of the rotation shaft **31a**) becomes larger, the effect of breaking the developer wall **W** becomes larger. However, because the developer adhered to the developer breaking member **61** is also increased, the developer adhered to the developer breaking member **61** may cause false detection of the toner sensor **43**. Therefore, it is **40** preferred that the width of the developer breaking member **61** be approximately 1 mm to 10 mm. In addition, in order to effectively break the developer wall **W** in the first developer delivery portion **40d**, it is necessary to set a protruding amount of the developer breaking member **61** (size in the rotation direction) so that the distal end of the developer breaking member **61** protrudes outside in a radial direction **45** from the rotation locus of the first helical blade **31b**.

In addition, when the developer breaking member **61** is **50** disposed in a vicinity of the detection surface of the toner sensor **43**, the toner adhered to the developer breaking member **61** may be detected by the toner sensor **43**, and hence the output of the sensor is badly affected. Therefore, it is necessary to dispose the developer breaking member **61** outside a detectable region of the toner sensor **43** in a depth direction of the developing container **40** (left direction in FIG. 13) with respect to the detection surface of the toner sensor **43**.

Other structure of third embodiment is the same as in the second embodiment described above.

In this embodiment, as described above, the first ribs **51a** and **51b** of the paddle portion **50** are provided with the developer breaking member **61** for breaking the developer wall **W**. **55** In this way, it is possible to prevent the developer from stagnating in a vicinity of the upstream side of the first developer delivery portion **40d**. Therefore, even if the developer amount

11

in the developing container **40** is small, or the developer is deteriorated so that its fluidity is lowered, the output value of the toner sensor **43** can be stabilized. In addition, control accuracy of toner supply from the toner container **5** to the developing device **4** is more improved.

In addition, as described above, the developer breaking member **61** protrudes outside in the radial direction from the rotation locus of the first helical blade **31b** of the first spiral **31**. In this way, the developer wall **W** formed in a region that is not affected by the transporting forces of the first spiral **31** and the second spiral **32** can be easily broken by the developer breaking member **61**.

In addition, as described above, the developer breaking member **61** is provided to the plurality of first ribs **51a** and **51b** at different positions in the direction of the rotation shaft **31a**. In this way, the developer wall **W** can be effectively broken.

In addition, as described above, the developer breaking member **61** is disposed at a position such as not to contact with the detection surface of the toner sensor **43**. In this way, it is possible to prevent the toner sensor **43** from detecting the toner adhered to the developer breaking member **61**.

Other effects of the third embodiment are the same as those of the second embodiment described above.

Next, supporting experiment that was performed for confirming the effects of the first embodiment and the second embodiment is described.

This supporting experiment was performed for Example 1 corresponding to the first embodiment, Example 2 corresponding to the second embodiment, and Comparative Example 1 that does not correspond to the embodiments.

In Example 1, the developing device **4** corresponding to the first embodiment was used. In other words, the ceiling height of the part of the first transport path **40a** facing the first developer delivery portion **40d** was set larger than the ceiling height of other part of the first transport path **40a** by 10 mm. The first spiral **31** without the paddle portion **50** was used.

In addition, a diameter and a pitch of the helical blade of the first spiral **31** and the second spiral **32** were 20 mm and 20 mm, respectively, and a rotational frequency was 34.5 rpm. Opening widths of the developer delivery portions **40d** and **40e** were 31 mm, and a gap between the developing container **40** and the first spiral **31** as well as the second spiral **32** was 1.5 mm. A circumference speed ratio (S/D) of the developing roller **20** to the photoreceptor drum **1** was 1.41. As to conditions of applying voltage to the developing roller **20**, V_{pp} was 1,600 V, a duty ratio was 45%, a frequency was 2.7 kHz, and V_{dc} (DC component) was 290 V. The developer (toner) having average mean grain diameter of 6.8 μ m was used.

In Example 2, the developing device **4** corresponding to the second embodiment was used. In other words, the first spiral **31** with the paddle portion **50** was used. Other structure of Example 2 was the same as in Example 1.

In Comparative Example 1, as illustrated in FIG. 14, unlike Examples 1 and 2, the ceiling height of the part of the first transport path **40a** facing the first developer delivery portion **40d** was the same as the ceiling height of other part of the first transport path **40a**. The first spiral **31** without the paddle portion **50** was used. Other structure of Comparative Example 1 was the same as Example 1.

Then, the sensor output value (V) and the toner weight (g) in continuous printing are measured every 500 sheet printing until 8,000 sheets for Examples 1 and 2 and Comparative Example 1. Note that the A4 size paper sheets were used, a coverage rate was set to 4%, and the experiment was performed at normal temperature. Results of Examples 1 and 2 and Comparative Example 1 are shown in FIGS. 15, 16, and 17, respectively.

12

In Example 1, as illustrated in FIG. 15, the toner weight was 128.6 g to 135.4 g, and a variation range of the toner weight was 6.8 g. In Example 2, as illustrated in FIG. 16, the toner weight was 129.1 g to 132.5 g, and the variation range of the toner weight was 3.4 g. In Comparative Example 1, as illustrated in FIG. 17, the toner weight was 115.7 g to 132.2 g, and the variation range of the toner weight was 16.5 g. In other words, in Example 1, the variation range of the toner weight was decreased to approximately 41% compared with Comparative Example 1. In Example 2, the variation range of the toner weight was decreased to approximately 21% compared with Comparative Example 1. Note that in Comparative Example 1, a white void was generated in a printed image after printing approximately 3,000 sheets.

As described above it was confirmed that it was possible to prevent the developer (toner) from being pressed by a pressure and being falsely detected by the toner sensor **43** by setting the ceiling height of the part of the first transport path **40a** facing the first developer delivery portion **40d** to be larger than the ceiling height of other part of the first transport path **40a**.

In addition, it was confirmed that it was possible to circulate the developer (toner) through the space between the first ribs **51a** and **51b**, to suppress adhesion of the developer to the first ribs **51a** and **51b**, and to improve control accuracy of toner supply by using the first spiral **31** equipped with the paddle portion **50**.

Note that the embodiments described above are examples in every aspect and should not be interpreted as limitations. The scope of the present disclosure is defined not by the above description of the embodiments but by the claims, which includes every modification within the meanings and ranges equivalent to the claims.

For instance, in the embodiment described above, the present disclosure can be applied not only to the monochrome printer illustrated in FIG. 1 but also various image forming apparatuses such as a digital or analog monochrome copier, color printer, color copier, or facsimile equipped with the developing device including the first agitating and mixing member and the second agitating and mixing member.

In addition, in the second and third embodiments described above, the paddle portion **50** of the first spiral **31** includes the pair of first ribs **51a** and **51b** at positions opposed to each other with respect to the center line of the rotation shaft **31a**. However, in the large first spiral **31** having a relatively large outer diameter of the first helical blade **31b**, the paddle portion **50** may have three or more first ribs. In this case, it is preferred to dispose the first ribs at constant intervals around the center line of the rotation shaft **31a**.

In addition, in the embodiments described above, there are used the first spiral **31** and the second spiral **32**, in which the helical blades **31b** and **32b** are continuously formed around the rotation shafts **31a** and **32a**. However, without limiting to the helical blades **31b** and **32b**, it is possible to use an agitating feeding member, for example, in which a plurality of semi-lunar plates (half-circular plates) are formed around the rotation shaft **31a** or **32a** alternately at a predetermined inclined angle.

In addition, in the embodiments described above, there is described an example in which the developer is the one-component developer containing only the magnetic toner. However, the present disclosure is not limited to this. It is possible to use two-component developer containing magnetic carrier and toner as the developer. Note that in the two-component developing method using the two-component developer, as the toner amount becomes smaller in the

13

developing device 4, a ratio of the magnetic carrier becomes larger. Therefore, the output value of the toner sensor 43 becomes larger.

What is claimed is:

1. A developing device comprising:
  - a developing container having a first transport path and a second transport path disposed substantially in parallel to each other, so as to store a developer containing toner;
  - a developer carrier supported in the developing container in a rotatable manner so as to carry the developer in the second transport path on a surface thereof;
  - a first agitating feeding member configured to agitate and feed the developer in the first transport path;
  - a second agitating feeding member configured to agitate and feed the developer in the second transport path to the opposite direction to the first agitating feeding member;
  - a first developer delivery portion configured to deliver the developer from the first transport path to the second transport path;
  - a second developer delivery portion configured to deliver the developer from the second transport path to the first transport path; and
  - a toner sensor disposed at a part of the first transport path close to the first developer delivery portion so as to detect toner amount or toner density in the developing container, wherein
  - a ceiling height of a part of the first transport path facing the first developer delivery portion is larger than a ceiling height of other parts of the first transport path;
  - the first agitating feeding member includes a rotation shaft and a transporting blade formed around an outer circumference surface of the rotation shaft, and
  - a part of the first agitating feeding member facing the first developer delivery portion does not have the rotation shaft and has a paddle portion including a plurality of first ribs parallel to the rotation shaft.
2. The developing device according to claim 1, wherein the paddle portion has a frame-like shape including the transport-

14

ing blade positioned at a most downstream side in a developer transport direction and the plurality of first ribs extending in parallel to the rotation shaft from the transporting blade.

3. The developing device according to claim 2, wherein the paddle portion has a frame-like shape surrounded by the transporting blade positioned at the most downstream side in the developer transport direction, two first ribs extending in parallel to the rotation shaft from the transporting blade, and a second rib extending perpendicularly to the rotation shaft so as to connect ends of the first ribs, and
- the second rib is connected to the rotation shaft at the opposite surface to the surface connected to the first ribs.
4. The developing device according to claim 2, wherein the transporting blade on the most downstream side in the developer transport direction constituting the paddle portion is formed so that at least a part thereof is overlapped with the first developer delivery portion in the rotation shaft direction.
5. The developing device according to claim 1, wherein the first rib of the paddle portion is provided with a developer breaking member for breaking a developer wall formed in the first developer delivery portion.
6. The developing device according to claim 5, wherein the developer breaking member protrudes outside in the radial direction from a rotation locus of the transporting blade of the first agitating feeding member.
7. The developing device according to claim 5, wherein the developer breaking member is provided to each of the plurality of first ribs at different positions in the rotation shaft direction.
8. The developing device according to claim 5, wherein the developer breaking member is disposed at a position such as not to contact with a detection surface of the toner sensor.
9. An image forming apparatus comprising the developing device according to claim 1.
